APPARATUS FOR USE IN THE MANUFACTURE OF SHEET GLASS

John M. Fisher, Ford City, Pa., assignor to Pittsburgh Plate Glass Company, a corporation of Pennsylvania

Application December 2, 1931. Serial No. 578,476

6 Claims. (Cl. 51—240)

My invention is particularly directed to mechanism to facilitate preparing plate glass for grinding and polishing operations. It is customary in the manufacture of plate glass to mount large sheets of it upon movable cars which pass beneath grinding and polishing elements and the glass must be securely attached to the cars. In order to provide a satisfactory mounting, a plaster bed is utilized in which the glass is embedded. The object of the present invention is to facilitate economical and satisfactory disposal of the plaster at the edge of the glass and of the car upon which it is mounted.

Heretofore the plaster has been disposed around the glass manually and such operation resulted in considerable loss of material, particularly by reason of the wet plaster overflowing the edge of the car. My invention is designed to obviate this waste and facilitate securing a satisfactory bed for the sheet glass. A better understanding of my invention may be had by reference to the accompanying drawings, in which like numerals indicate corresponding parts.

Fig. 1 is a plan view, parts being broken away, of cars carrying sheet glass embedded in plaster in preparation for grinding and polishing, in which the invention is shown in one form of its application; Fig. 2 is a transverse sectional view taken substantially along the line II—II of Fig. 1; Fig. 3 is a fragmentary sectional view of my invention in which certain minor modifications are embodied; Fig. 4 is likewise a fragmentary sectional view of my invention in which a beveled edge is imparted to the plaster; and Fig. 5 is a fragmentary sectional view of another form of the invention that is particularly adapted for application in preparing a bed for relatively thin plate glass.

In the ordinary course of grinding and polishing plate glass, a car 1 is utilized which is mounted to ride upon a track 2 in order to present glass 3 mounted upon the flat top of the car to grinding and polishing elements, not shown. The glass is ordinarily embedded in wet plaster and pegs 4 are mounted near the edges of the car in order to provide anchorage for the plaster and consequently present a firm bed for the glass. My invention is particularly concerned with the formation of the edge of the plaster bed and includes a belt 5 trained about a plurality of pulleys 6 and guide shoes 7. A plurality of pulleys 8 are mounted at the outside edge of the mechanism to retain the belt positively in position. In order to insure close engagement of the belt with the edge of the car, and consequently plas-

ter carried thereon, the guide shoes may be formed of separable portions 9 and 10 between which springs 11 are inserted to force the belt yieldingly against the edge of the car. Further adjustment is presented by mounting the guides and pulleys upon a supporting bracket 12 by means of bolts 13 that are disposed in slots in the bracket. The bracket is attached to a guard member 14 that is ordinarily utilized to prevent plaster from getting upon the track 2, since it is particularly desired to have the car travel very smoothly during the grinding and polishing operations.

It will be apparent from the foregoing description that the belt provides a yieldable abutment for the plaster that is spread upon the top of the car and by reason of the belt being mounted upon pulleys, it travels with the car as a result of frictional engagement. Since the belt travels with the car, there is no tendency to disturb the proper setting of the wet plaster and consequently the formation of a firm retaining bed for the sheet of plate glass. Obviously the plaster can not overflow the edge of the car and consequently all waste in this respect is avoided.

A slight modification of my invention is shown in Fig. 3. A solid guide shoe 15 is utilized and a yielding force is applied to engage the belt with the edge of the car by means of a pivotally mounted bracket 16 secured to the guard 14, as indicated at 17. In order to force the pivoted bracket 16 toward the edge of the car, bolts 18 are disposed through the bracket 14 and the bracket 16 and springs 19 are employed to secure the bracket 16 in adjusted position. The operation of this form of the device is much the same as the form shown in Figs. 1 and 2.

Another slight modification is shown in Fig. 4 in which a saving of material is achieved by utilizing a guide shoe 20 which is provided with an angular portion 21 to force the belt over the edge of the table thereby to bevel the plaster disposed thereon. Pulleys 22 are mounted at intervals within the guide member 20 which is provided with openings to permit the pulleys to engage the belt. A yieldable adjustment of the belt against the edge of the table may be achieved in the manner shown in Fig. 3.

Still another form of my invention is shown in Fig. 5 in which a flat stationary belt 23 is utilized which is secured to a bracket 24 pivotally mounted upon the guard 14, as indicated at 25. In this form of the invention, the belt as shown engages the top edge of the car and is forced against the plaster by means of a handle 26. Inward move-

ment of the belt may be predetermined by means of an adjustable bolt 27 mounted upon the bracket 24 adapted to engage a lug 28.

It will be clear from the foregoing description of the various forms of my invention that a simple device is provided which insures economical manipulation of the wet plaster to secure a satisfactory and firm bed for the plate glass upon the cars. As will be apparent from the description of the various forms of my invention, it is obvious that the principles thereof may be utilized to advantage in many applications and consequently the invention should not be limited except as indicated in the appended claims.

15. What I claim is:

1. The combination with a car having a flat supporting top for carrying a sheet of glass to be surfaced of less width than said top, and means for retaining the plaster used between the edge of the sheet and the edge of the car, comprising a retaining member for the plaster which extends along the edge of the car supported independently of the car and past which the car moves.

25. 2. The combination with a car having a flat supporting top for carrying a sheet of glass to be surfaced of less width than said top, and means for retaining the plaster used between the edge of the sheet and the edge of the car, comprising a retaining member for the plaster in the form of an endless belt, which extends along the side edge of the car and projects above said top past which the car moves.

3. The combination with a car having a flat supporting top for carrying a sheet of glass to be surfaced of less width than said top, and means for retaining the plaster used between the edge of the sheet and the edge of the car,

comprising a retaining member for the plaster which extends along the edge of the car supported independently of the car and past which the car moves, and means yieldingly pressing the member against the edge of the car.

80. 4. The combination with a car having a flat supporting top for carrying a sheet of glass to be surfaced of less width than said top, and means for retaining the plaster used between the edge of the sheet and the edge of the car, comprising a retaining member for the plaster in the form of a strip which extends along the edge of the car, and held against longitudinal movement past which the car moves.

85. 5. The combination with a car having a flat supporting top for carrying a sheet of glass to be surfaced of less width than said top, and means for retaining the plaster used between the edge of the sheet and the edge of the car, comprising a retaining member for the plaster in the form of a strip which extends along the edge of the car resting on the top thereof and held against longitudinal movement past which the car moves.

90. 6. The combination with a car having a flat supporting top for carrying a sheet of glass to be surfaced of less width than said top, and means for retaining the plaster used between the edge of the sheet and the edge of the car, comprising a retaining member for the plaster in the form of an endless belt, which extends along the side edge of the car and projects above said top past which the car moves, and means for causing the portion of the belt lying above the top of the table to incline toward the center line of the 105 table so as to bevel the plaster.
